US0D1108403S

(12) United States Design Patent (10) Patent No.: US D1,108,403 S
(45) Date of Patent:  Jan. 6, 2026

(54) EARPHONE

(71) Applicant: Tzuka Limited, Loughborough (GB)

(72) Inventor: Thomas Jelliffe, Loughborough (GB)

(73) Assignee: Tzuka Ltd, Loughborough (GB)

() Term: 15 Years

(21) Appl. No.: 35/521,925

(22) Filed: Jul. 17, 2024

(80) Hague Agreement Data

Int. Filing Date: Jul. 17, 2024

Int. Reg. No.: DM/238888

Int. Reg. Date: Jul. 17, 2024

Int. Reg. Pub. Date: Aug. 9, 2024

(30) Foreign Application Priority Data
